(57) **CLAIM**

We claim the ornamental design for a speed display screen with graphical user interface, as shown and described.

DESCRIPTION

FIG. 1 is a front view of a speed display screen with graphical user interface showing our new design; and, FIG. 2 is another front view of the speed display screen with graphical user interface of FIG. 1 showing alternative broken line subject matter.

The outermost dot-dash line and the dot-dash broken line showing of the rounded quadrilateral shapes, arrow icons and "OK" text illustrate an electronic device. The dot-dash line at the periphery of the figure illustrate the display screen, and the remaining broken line showing of alphanumeric characters illustrate portions of the graphical user interface. None of the broken lines form part of the claimed design.
